UNITED STATES PATENT OFFICE.

SIEGMUND LOEWE, OF BERLIN, GERMANY.

PROCESS FOR TESTING SPARK STATIONS.

No Drawing.

Application filed July 27, 1921. Serial No. 487,821.

(GRANTED UNDER THE PROVISIONS OF THE ACT OF MARCH 3, 1921, 41 STAT. L., 1313.)

To all whom it may concern:

Be it known that I, SIEGMUND LOEWE, a citizen of the German Republic, residing at Berlin, Germany, have invented certain new and useful Improvements in Processes for Testing Spark Stations (for which I have filed applications in Germany, Sept. 15, 1915, now Patent 318,996; Denmark, Apr. 16, 1920; Poland, July 2, 1920; Sweden, Dec. 30, 1919), of which the following is a specification.

Among the requirements for the proper working of a spark station is the emission of a pure tone. The production of this is accomplished either by adjustment to the proper potential or by processes which are known under the name of "auxiliary sparking". The use of the "auxiliary spark" broadens the range of potential within which a good tone is obtained, without the potential regulation itself being entirely abandoned.

Testing as to whether the tone produced is pure or not, has previously been accomplished by listening to the tone produced by means of a circuit containing a telephone and a detector, or by observing the spark image in a rotating helium tube.

Either method is only useful under very definite conditions, and is not sufficient for all requirements which might be set up. With the telephone, for example, often the oscillation of the telephone membrane itself becomes so strong that the character of the tone is completely changed. Likewise it is frequently found that the spark image to be observed in the rotating helium tube has a relatively regular appearance, without the tone being pure.

Even more frequently the spark image observed is irregular for other reasons; for example, if the number of revolutions of the driving motor for the helium tube is not in a definite ratio to the sequence of sparks, or, if the helium tube passes through fields of different strengths in its change of position, so that it lights more easily in some positions than in others.

Likewise at the detector, frequently, the reverse is the case:

In the detector circuit, the tone sounds poor, whereas in reality it is found very

good, upon testing by receiving at a distance.

In any event, heretofore, objective means have been lacking, which indicate the quality of the tone.

By this invention, the process of testing the tone is to be brought to the form of a reading of an instrument or by the indication by such an instrument. Several possibilities are offered for this. If it be observed especially that a good tone can only occur if all phenomena in the sending circuit repeat themselves very exactly in period; that a poor tone, on the contrary, is always present if any irregular phenomena come into play; then it is immediately recognized that all means which permit deciding whether the phenomena in the sending circuit repeat themselves with exact regularity or not, at the same time afford the possibility of investigating the quality of the tone. Let us take, for example, the drop of potential at the condenser as a starting point for testing the tone. A pure tone then is always produced if the drop of potential at the condenser exactly repeats itself periodically; the period of the repetition corresponding with the period of the generator tho it need not. It can, for example, be a higher or lower multiple of the same. It may also consist of groups which repeat themselves periodically (partial sparks).

The problem now exists of determining whether the drop of potential at the condenser repeats itself periodically or not; for example, whether besides its periodical repetition, more or less frequent disturbances of the drop of potential occur.

The indicating devices may have different properties. They may, for example, respond to these disturbances; then the characteristic that a good tone is present would be that the instrument remains in its position of rest; or the instrument can as well respond to the periodical phenomenon as well as to the disturbing one, then in most cases the criterion for a good tone will consist in a very quiet deviation of the instrument. The instrument may finally only respond to the periodical phenomenon alone, then a measurement of the occurrence of disturbances

would be found, for example, by the comparison of the energy expended and that obtained in useful form (potential, current, output). The instrument itself in no way 5 need be exclusively an electrical one; often-times the problem of investigating the phenomena in the sending circuit of the station, with regard to their periodicity, may also be solved by mechanical or partly mechanical, partly electrical means, and mechanical as well as electrical resonators are useful for 10 this purpose.

The use of the process might be described by an example.

15 If we include, for example, an ordinary direct-current ammeter in the primary circuit (exciting circuit) of a sending station for wireless telegraphy, then a slight reflection shows that this instrument can give no 20 deflection, if actually a spark is produced in the primary circuit at each alternation, assuming that the spark which is produced by the positive half-wave breaks at the same potential as that which gives the negative 25 half-wave. The direct-current instrument is excited ballistically by each spark, and remains at rest, as the number of coulombs passing through the cross-section of the conductor of the primary circuit is, under this 30 assumption, equal but opposite in the two sparks; naturally assuming that the number of sparks is sufficiently great so that the instrument does not follow the individual spark impulses. If however only one spark 35 occurs during each positive half-wave, whereas during each negative half-wave two sparks pass, then the direct-current instrument would show a deflection towards the negative side. If for example such a double 40 spark only occurred more or less frequently during one half-wave—the typical case of disturbance—then the ammeter sways back and forth and thus shows that disturbances are present. It is then possible, for example 45 by regulation of the potential, to permit the second spark to occur always or never, so that the deflection of the ammeter returns to 0 or assumes a constant value, wherewith in both cases, a pure tone is obtained under 50 the circumstances.

In this case the characteristic for the occurrence of a good tone is likewise that the indicator of the instrument remains at rest, indifferently where it be, whether at 0 or at 55 any deflection. This deflection shows, however, much more at the same time. Under all conditions in which in equal times, the same number and the same strength, but oppositely directed sparks are produced, the 60 instrument remains at rest and at 0. This is, for example, the case if in each alternation or at the third, fifth, seventh . . . a spark is produced (counting from that 65 alternation at which a spark was last produced). But if a spark passes at each sec-

ond, fourth, sixth . . . alternation, then the instrument shows a constant positive or negative deflection.

The occurrence of a good tone can therefore not (only) be recognized by the indicator remaining at rest, but also the form of the tone, whether fundamental, third, octave, fifth, etc., by the reading of the deflection of the indicator. In this modification, by way of example, there is therefore a 75 directly-indicating instrument, in the sense of the invention.

Further, the same instrument might also be intercalated at other points of the sending circuit; for example, in parallel to the exciting circuit condenser or in the secondary charging conductor of the transformer. Naturally, the damping of this instrument is to be so proportioned that on the one hand it reacts sufficiently to the disturbances which occur in practice, on the other hand however not being immediately thrown across the scale by every disturbance occurring.

Also, devices may be provided on the instrument which indicate the occurrence of a good tone by the coming to rest of a member which oscillates at other times; or vice versa, by the starting to oscillate of a member at other times remaining at rest. The inscription is selected according to the construction of the instrument; for example, so that when an indicator comes to rest, an inscription is legible, for example "Tone good." Likewise the instrument may be directly calibrated in tones, so that the occurrence of a fundamental, third, etc., can be read off directly.

It would lead us too far to go into the numerous possibilities of solution which are still offered for the principle set up here. To name only one further example: Very definite, characteristic points and peaks exist in the shape of the curve of the primary current at good tones, which naturally are to be referred to the disturbance of the course of the primary current by the starting of the spark.

In the generator circuit of a sending station for wireless telegraphy, however, the instrument described above is not useful by itself, as in this circuit a direct current can never occur. In spite of this, the recurrence of the same points and peaks in the curve for the current for a particular system is typical of the occurrence of good tones.

It is well-known in alternating current technics how such distortions of current may be observed (by resonators, etc.).

Here the possibility is also offered of testing the presence of a good tone by the occurrence of the peaks and points characteristic of a good tone.

The most direct are naturally those methods which are based on the sparks themselves

and their effects; whether the indicator is of optical, thermal, mechanical, or electrical form, is of itself of no importance; and it requires only some method of transmission 5 to provide a tone indicator in any manner, of the form described.

I claim:

1. The process of testing the purity of the tone of a radio sending system, which 10 consists in connecting a direct-current instrument to a part of the system undergoing periodical electrical changes and observing whether the direct-current instrument gives a constant reading.

15 2. The process of testing the purity of tone of a radio sending system which consists in connecting a direct-current ballistic instrument, so that it is subjected to the changes in potential on a condenser of said system 20 and observing whether the reading of the instrument is constant.

25 3. The process of discriminating between the fundamental and overtones while testing the purity of tone of a radio sending system, which consists in connecting a ballistic direct-current instrument so that it is subjected to the changes of potential on a condenser in said system, and observing whether the reading of the instrument is constant 30 to determine the purity of the tone and whether the reading of the instrument differs from zero to determine the presence of harmonics in the tone.

35 4. The process of adjusting a radio sending system to obtain purity of tone which consists in connecting a direct-current ballistic instrument so that it is subjected to the potential upon a condenser of said system,

observing the reading of the instrument, and adjusting the amplitude of the impressed 40 potential until said reading is constant.

5. The process of determining whether the phenomena in a radio system repeat themselves exactly, which consists in applying to the system an instrument that gives zero 45 reading for exact repetition of said phenomena and a static reading other than zero for a repetition of a kind giving rise to even harmonics.

6. The process of determining the purity 50 of tone in a radio sending system of the spark type, which consists in so connecting a direct-current instrument thereto that it is subjected to electrical changes accompanying each spark, said instrument being 55 sufficiently dead-beat to prevent it responding to the changes accompanying a single spark.

7. The process of discriminating, in testing the action of the radio sending system 60 of the quenched spark type, between a single spark in each half cycle and a plurality of sparks in each half cycle, which consists in so connecting a ballistic dead-beat direct-current instrument to the system that it is 65 subjected to electrical changes accompanying each spark and observing whether the reading of said instrument is zero.

8. The process of testing the purity of 70 tone of a radio sending system which consists in applying thereto an instrument responsive to the peak phenomena accompanying each period.

In testimony whereof I affix my signature.

DR. SIEGMUND LOEWE.
